JACK STRUCTURE

Ernest Strom, St. Paul, Minn., assignor to Vulcan Manufacturing Co., Inc., St. Paul, Minn., a corporation of Minnesota

Application November 10, 1941, Serial No. 418,462

6 Claims. (Cl. 254—93)

My present invention relates to a jack structure of the hydraulic bumper type.

One object of the invention is to provide a relatively light, yet powerful jack of this general character which is comparatively inexpensive to manufacture.

Another object is to provide a hydraulic jack structure having novel means for transferring oil from a reservoir to a lifting cylinder or from the cylinder back to the reservoir, such means including a partition member between the lifting cylinder and reservoir wherein a pump structure is located.

Still another object is to provide the partition member assembled by screwing of the reservoir into the lifting cylinder.

A further object is to provide an intake check valve in the partition member which is movable laterally and an outlet valve which is movable vertically, the pump plunger being coactable with both valves to move them to an unseated position to permit return of oil when desired, screw-threaded means being provided to effect a fine adjustment of the valves for regulating the speed of return of the jack.

Still a further object is to provide a lifting hook on the jack structure which may be vertically adjusted to any one of several different positions by a simple lifting movement of the hook and sliding thereof along the lifting cylinder to a position where a lug of the hook may enter a desired one of a plurality of spaced openings formed in a channel shaped member arranged longitudinally of the lifting cylinder.

Still a further object is to provide a foot member for the jack structure which may be formed of heavy sheet metal and secured to the jack by a cotter key or the like in such manner that the foot plate may be canted to an angular position to conserve space when storing the jack on the tool box or under a seat of the automobile.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a perspective view of a jack structure embodying my invention;

Figure 2 is an enlarged vertical sectional view with parts broken away to conserve space on the drawing;

Figure 3 is a sectional view on the line 3—3 of Figure 2, and

Figure 4 is a sectional view similar to the central portion of Figure 2, showing certain parts in a different position.

On the accompanying drawing, I have used the reference numeral 10 to indicate a foot plate. The plate 10 may be pressed from heavy sheet metal, with a socket at 13 and a plurality of depressions 16 adapted to bite into the ground when using the jack. The plate 10 also has a pair of groovelike extensions 15 in opposite directions from the socket 13.

A stationary plunger 12 in the form of a tube or 20 rod has a rounded lower end seated in the socket 13 and retained therein by a cotter pin 14. The axis of the pin 14 is crosswise relative to the grooves 15 so that when the jack is stored in the tool box or under the seat of the automobile, the 25 foot plate may be tipped up to a position closely adjacent the plunger 12 to conserve space.

A lifting cylinder 17 surrounds the stationary plunger 12 and is guided relative thereto by packing 18 and a guide ring 19. The upper end of the lifting cylinder 17 has a partition member P seated therein and retained in its seated position by a reservoir 20. The reservoir 20 is threaded into the lifting cylinder 17 against a flange 21 of the partition member P, which effects compression of a gasket washer 22 between the partition member and an inclined shoulder of the lifting cylinder. At the same time, packing 23 is compressed between the reservoir 20 and the upper end of the lifting cylinder to effect 35 a seal at this point.

The partition member P has an intake valve seat member 24 screwed laterally into it. An intake check valve 25 of ball type is adapted to seat thereagainst under the bias of a spring 26. 45 An outlet check valve 27 is arranged to be normally seated against a seat 28 of the partition member P by a spring 29. A cotter key 30 retains the spring 29 in position and also a follower washer 31 for the gasket washer 22.

A pump cylinder 31 is provided in the form of 50 a tube threadedly mounted in the upper end of the partition member P. A pump plunger 32 is reciprocable therein and has a reduced portion 33 on its lower end.

The pump plunger 32 extends upwardly through a top member 34 of the reservoir 20, coacting with

packing 35 therein to effect an oiltight seal. The upper end of the pump plunger is threaded into a fitting 36 which in turn is connected with a cap 37. An actuating sleeve 38 is secured to the cap 37 as by a friction or press fit and a suitable welded connection after the parts are associated. A lock nut 39 is mounted on the pump plunger 32 to retain it in the fitting 36.

The fitting 36 has a coarse threaded exterior adapted to coat with threads in a boss 40 of the reservoir top 34. The reservoir has a filler plug at 41 and the actuating sleeve 38 has a vent opening at 42, the purpose of which will herein-after be described.

A lifting hook H is vertically adjustable with respect to the lifting cylinder 17. The hook H is formed on a loop member having a front part 43, side parts 44 and a rear part 45. The front part 43 is located at a substantially lower elevation than the rear part 45. The part 45 has a lug or projection 46 adapted to selectively enter any one of a plurality of openings 47 formed in a channel shaped member 48. The member 48 has its flanges shaped to fit the lifting cylinder 17 and suitably secured thereto as by spot welding, indicated at 49.

Practical operation

In the operation of my jack structure, the hook member H may be roughly adjusted to the desired elevation on the lifting cylinder 17 by tipping it upwardly as to the dotted position of Figure 2, vertically adjusting it, and at the desired height permitting the lug 46 to enter the opening 47 there found. The lifting hook may then be elevated by moving the cylinder 17 upwardly relative to the plunger 12, which is accomplished by actuating the pump plunger 32. On the upstroke, as shown in Figure 4, oil will be drawn in through the valve 25 from the reservoir 20 and into the pump cylinder 31. On the down stroke, this oil closes the valve 25 and opens the valve 27 as it is displaced from the pump cylinder 31 and the vertical bore in the partition member P. The check valves will hold the load at any desired elevation.

When it is desirable to lower the jack, the actuating sleeve 38 is pushed downwardly as far as it will go, which will result in the reduced end 33 of the plunger 32 almost touching the valve 25. The sleeve 38 is then rotated clockwise to cause the threaded fitting 36 to rotate in the hub 40. This operation causes a relatively slow movement downward of the pump plunger 32, with plenty of leverage for causing the reduced end 33 to first open the valve 25 by forcing it laterally and then finally opening the valve 27 by forcing it downwardly. The degree of opening of the valve 27 will determine the speed of descent of the jack and the speed can be nicely controlled by rotating the sleeve 38. When the threads 36 are right hand, then clockwise rotation of the sleeve 38 will lower the pump plunger 32 for the valve opening operation.

During the downward movement of the sleeve 38 as it is reciprocated, the air trapped therein may pass freely out through the vent 42. As the sleeve is moved upwardly, air passes freely in through the vent 42 so as to prevent any drag on the pumping operation. The filler plug 41 may be removed and additional oil placed in the reservoir 20 when necessary. Leakage of the oil from the jack is effectively prevented, however, by the lower packing 18 and the upper packing 35.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a jack structure, a stationary plunger, a lifting cylinder telescopically mounted thereon, a reservoir screw threadedly mounted in and forming a continuation of said lifting cylinder, means for transferring fluid from said reservoir to said lifting cylinder comprising a partition member having a flange engaged by said reservoir as it is screwed into said lifting cylinder and thereby retained in position between the reservoir and lifting cylinder, a pump cylinder carried by said partition member, intake and outlet check valves in said partition member opening respectively from said reservoir and into said lifting cylinder, a pump plunger reciprocable in said pump cylinder, an actuator therefor comprising a sleeve connected with said pump plunger, said pump plunger extending through the top of said reservoir, said sleeve being telescopically mounted on said reservoir, said pump plunger being engageable with said intake valve to shift it off its seat and then with said outlet valve to shift it off its seat to permit return of oil through said outlet and intake valves from said lifting cylinder into said reservoir, and means to cause such engagement of said pump plunger with said valves.

2. In a jack structure, a stationary plunger, a lifting cylinder telescopically mounted thereon, a reservoir screw threadedly mounted on said lifting cylinder, means for transferring fluid from said reservoir to said lifting cylinder comprising a partition member confined between said reservoir and said lifting cylinder by their screw threaded connection, a pump cylinder carried by said partition member, intake and outlet check valves in said partition member opening respectively from said reservoir and into said lifting cylinder, said intake valve opening laterally and said outlet valve opening downwardly, a pump plunger reciprocable in said pump cylinder, and an actuator therefor comprising a sleeve connected with said pump plunger, said pump plunger extending through the top of said reservoir to said sleeve, said sleeve being telescopically mounted on said reservoir, said pump plunger being engageable with said intake valve to shift it laterally off its seat and then, after passing said intake valve, being engageable with said outlet valve to shift it downwardly off its seat to permit return of oil through said outlet and intake valves.

3. In a jack structure, a stationary plunger, a lifting cylinder telescopically mounted on the upper end thereof, a reservoir separate from and mounted on said lifting cylinder, means for transferring fluid from said reservoir to said lifting cylinder comprising a partition member between said reservoir and said lifting cylinder, a pump cylinder carried by said partition member, intake and outlet check valves in said partition member opening respectively from said reservoir and into said lifting cylinder, and a pump plunger reciprocable in said pump cylinder and extending through the top of said reservoir, said pump plunger being engageable with said intake valve to shift it off its seat and

pass it and being then engageable with said outlet valve to shift it off its seat to permit return of oil through said outlet and intake valves from said lifting cylinder into said reservoir, said plunger being smaller than the passageway between said valves to permit such return.

4. In a jack structure, a plunger, a lifting cylinder telescopically mounted thereon, a reservoir mounted on said lifting cylinder, means for transferring fluid from said reservoir to said lifting cylinder comprising a partition member between said reservoir and said lifting cylinder, a pump cylinder carried by said partition member, intake and outlet check valves in said partition member opening respectively from said reservoir and into said lifting cylinder, said intake valve opening laterally and said outlet valve opening downwardly, a pump plunger reciprocal in said pump cylinder, and an actuator therefore comprising a sleeve connected with said pump plunger, said pump plunger extending through the top of said reservoir to said sleeve, said plunger being engageable with said intake valve to shift it laterally off its seat and then with said outlet valve to shift it downwardly off its seat to permit return of oil through said outlet and intake valves.

5. A jack structure comprising a stationary plunger, a lifting cylinder telescoped thereon, a reservoir, pump and check valves to pump oil from said reservoir into said lifting cylinder

5 to displace said stationary plunger therefrom, a lifting hook on said lifting cylinder comprising a loop portion encircling the lifting cylinder, a lug projecting inwardly from said loop portion, a supporting hook on said loop portion opposite said lug, and an elongated channel shaped element longitudinally arranged on said lifting cylinder with its flanges secured thereto and its web spaced therefrom, said channel shaped element having spaced openings through its web to selectively receive said lug therethrough, the hook side of said loop portion depending below the lug side thereof to permit tipping of the loop upwardly at the hook end to unlock said lug relative to an opening of said channel shaped element to permit longitudinal adjustment of the lifting hook thereon and coaction of said lug with another selected opening.

20 6. In a jack structure, a plunger, a lifting cylinder telescoped thereon, a reservoir, pump and check valves to pump oil from said reservoir into said lifting cylinder to displace said plunger therefrom, a lifting hook on said lifting cylinder comprising a loop portion encircling the lifting cylinder, a lug projecting inwardly from said loop portion, a supporting hook on said loop portion opposite said lug, and an elongated channel shaped element longitudinally arranged on said lifting cylinder with its flanges secured thereto and having spaced openings in its web to selectively receive said lug.
